UNITED STATES PATENT OFFICE.

JOHN DARBY, OF PHILADELPHIA, PENNSYLVANIA, AND CLAYTON W. OLD, OF MONT-
CLAIR, NEW JERSEY, ASSIGNEES, BY MESNE ASSIGNMENTS, TO SHUR LOC ELEVA-
TOR SAFETY CORPORATION, OF NEWARK, NEW JERSEY, A CORPORATION OF NEW
JERSEY.

ELEVATOR.

Application filed April 30, 1926. Serial No. 105,742.

This invention is concerned particularly with the operation of elevator shaft doors, such as are commonly actuated manually through the intermediary of toggle levers.

- 5 One object of the invention is to provide improved means, dependent upon the movement of the toggle lever system, for preventing the opening of the shaft door from the outside when it is in nearly closed 10 position. Another object of the invention is to provide improved means, actuated by the movement of the toggle levers to lock in neutral position the control element 15 by which the movement of the car up or down is determined by the operator.

The invention will be described more fully hereinafter with reference to the accompanying drawings in which it is illustrated as embodied in a convenient and practical form 20 and in which:

Figure 1 is a view in elevation from the inside showing in full lines a portion of a shaft door and its operating toggle system in closed position, the position of the 25 door and its toggle system when the door is open being indicated by broken lines.

Figure 2 is a view partly in elevation as seen from the left-hand, of the parts shown in Figure 1, and showing also, partly 30 in elevation and partly in vertical section, a portion of the elevator car with its control element and locking rod.

Figure 3 is a detail view in elevation and on a larger scale of some of the parts 35 shown at the right hand in Figure 1.

Figure 4 is a detail view in elevation and on a larger scale of some of the parts shown at the lower right-hand corner of Figure 1.

Figure 5 is a detail view in elevation 40 of the parts shown in Figure 4 and at the lower left-hand corner of Figure 2, as seen from the left-hand in Figure 4.

Figure 6 is a detail view in elevation 45 illustrating the connection between the toggle lever system and the door.

Figure 7 is a view in section on the plane indicated by the line 7—7 of Figure 6.

In the embodiment of the invention illustrated in the drawings, a shaft door, arranged 50 to slide horizontally, is shown at *a*, with an operating toggle lever system consisting of the member *b*, pivotally connected with the door *a*, as shown at *a'* in Figures

1, 6 and 7, and provided with an operating handle *b'*, and a second member *b*² pivoted 55 upon a bracket *c* at one side of the shaft-way, pivotally connected with the member *b* at *b*³ and formed as usual for engagement with a stop pin *b*⁴ to prevent flexing of the toggle lever system beyond the straight line 60 position. The toggle lever member *b*² is also connected, as usual, through a rod *d* with a spring containing cylinder *d'* by which the door is checked in its opening movement and by which the closing movement of the door may be effected in whole 65 or in part.

On the toggle member *b*² is pivotally mounted a dog *e* which hangs normally by 70 its own weight in the position shown in Figures 1 and 3 and in the movement of the toggle member, in the first part of the opening movement of the door and also in the last part of the closing movement of the door, rides over a rack *c'* formed on the 75 bracket *c* or otherwise fixed on the wall of the shaft-way. In the opening movement of the door, the dog rides freely over the rack *c'* and offers no obstacle to the opening of the door, but after the dog has been 80 raised above the rack, as in the complete opening of the door, as indicated by broken lines in Figure 1 and by broken lines in the extreme upper or right-hand position, indicated in Figure 3, and thereafter, as in the 85 last of the closing movement of the door, the dog rides down over the rack, the dog is then swung to the position shown by broken lines in Figure 3, in the intermediate position of the toggle lever. At this time, 90 in the movement of the door, the leading edge of the door is near the left-hand jamb of the door and experience has shown that at such times it sometimes happens that a belated traveler, seeing that the door has 95 not been completely closed, inserts his hand in the open space between the door and the jamb and tries to reopen the door. Throughout the greater part of the movement of the door, even in closing, the control element of 100 the car is locked in neutral position, so that the car cannot be made to move either up or down, but when the door is nearly closed, that is, with its leading edge within a few 105 inches of the adjacent jamb, the control element is usually unlocked, so that the reopen-

100
105

ing of the door at that time might result in an accident. It becomes desirable, therefore, to prevent the reopening of the door at such time and it will be seen that when the dog e , in the last of the closing movement of the door, assumes the position shown in Figure 3, with its tooth e' in engagement with the rack c' , it will resist any movement of the toggle lever system in a direction in accord with the opening movement of the door and will, therefore, prevent such undesirable opening of the door. When, however, the door reaches or nearly reaches its completely closed position, the tooth e' of the dog e will pass below the rack c' and the dog will then swing to its normal position, shown in full lines in Figures 1 and 3, so that it will permit the opening of the door from its fully closed position, when there can be no longer danger of accident.

It has been found desirable, in the development of the present invention, not only to make the locking of the door, as described, dependent upon the movement of the toggle lever system, through the mounting of the dog e on one member of said system, but to make the locking of the elevator control also dependent upon the movement of the toggle lever system, rather than upon the movement of the door itself. Accordingly, in order to carry out this part of the invention, there is pivotally mounted on the toggle lever member b^2 a bell crank lever f which carries at the end of one arm f' thereof a roller f^2 arranged to travel against and on the edge of a control plate c^2 . In the first part of the upward movement of the toggle member b^2 in the first part of the opening movement of the door, the roller f^2 rides against the nearly vertical edge of the plate c^2 , whereby the bell crank lever f is swung on its axis in a contrary clockwise direction, increasing materially the upward swinging movement of the other arm f^3 of the bell crank. As soon, however, as the toggle member b^2 has swung upward through a portion of its full movement, the roller f^2 rides on the substantially concentric upper edge of the plate c^2 so that there is no further swinging of the bell crank lever on its axis during the continued movement of the toggle member. The bell crank lever is thus caused to have an effective movement only during the first part of the opening movement of the door, this effective movement, through suitable operative connections, being made to bring about at this time the locking of the control element of the car. As shown, the arm f^3 of the bell crank lever f is connected by a link f^4 with one arm g' of the bell crank g mounted on a bracket g^2 , preferably at the bottom of the door opening. The other arm g^3 of the bell crank g is operatively engaged with a plunger h mounted for horizontal movement in the

bracket g^2 . Thereby, in the beginning of the opening movement of the shaft-way door, the plunger h is projected from the shaft-way wall toward the car, the floor of which is indicated at i in Figure 2. On the car is supported for horizontal movement a shoe k , which is carried by a slide k' mounted in guides k^2 carried by a bracket k^3 . The slide k' in the embodiment of the invention illustrated, is connected by a link l , through a yielding member l' , with an arm l^2 which is fixed on a shaft m mounted in a bracket i' on the under-side of the car floor. The shaft m has secured thereto a two-armed lever m^1, m^2 , one arm of which is weighted, as at m^3 , to maintain the arm normally in the position shown in Figure 2 and is connected at its end with the locking rod n which, as is well understood is adapted to engage the notched member o' of the control element o to hold the same in neutral position and therefore prevent movement of the car either up or down as soon as the opening movement of the shaft-way door has commenced. The other arm of the lever m^1, m^2 is connected by a cable m^4 with a drum m^5 to effect disengagement of the locking rod from the control element in emergency, such movement being permitted by the yielding connection l' .

It will be understood that various changes in details of construction and arrangement can be made to suit different conditions of use and that, except as pointed out in the claims, the invention is not restricted to the precise construction and arrangement shown and described herein.

We claim as our invention:

1. In an elevator, the combination of a shaft-door, a toggle lever system to operate the door, a rack fixed in position adjacent to the fixed pivot of the toggle lever, and a weighted dog pivotally mounted on the adjacent toggle member, the dog riding freely over the rack in the movement of the toggle in the opening movement of the door and engaging the rack in the movement of the toggle member in the last of the closing movement of the door to prevent movement of the toggle member in the opposite direction and opening movement of the door.

2. In an elevator, the combination of a shaft-door, a car, a control element for the car, a lock for the control element, a toggle lever system to operate the door, a lever carried by one of the toggle elements, a fixed control plate for co-operation with said lever in the movement of the toggle member, and intermediate devices whereby the control lock is actuated through the movement of said lever.

3. In an elevator, the combination of a shaft-door, a car, a control element for the car, a lock for the control element, a toggle lever system to operate the door, a lever

carried by one of the toggle elements, a fixed control plate for cooperation with said lever in the movement of the toggle member, a shoe mounted movably on the car and operatively connected with the lock, a plunger mounted on the shaft-way for cooperation with the shoe, and intermediate devices

whereby the plunger is moved by the movement of said lever.

This specification signed this 28th day of 10 April, A. D. 1926.

JOHN DARBY.
CLAYTON W. OLD.
